Primary Examiner — Marissa J Cash(74) *Attorney, Agent, or Firm* — LKGGlobal | Lorenz & Kopf, LLP(57) **CLAIM**

The ornamental design for an aircraft, as shown and described.

DESCRIPTION

FIG. 1 is a front perspective view of an aircraft showing our new design;

FIG. 2 is a front view thereof;

FIG. 3 is a back view thereof;

FIG. 4 is a first side view thereof;

FIG. 5 is a second side view thereof;

FIG. 6 is a top view thereof; and,

FIG. 7 is a bottom view thereof.

The broken lines illustrate environment and structure that form no part of the claimed design.

1 Claim, 5 Drawing Sheets(56)
